UNITED STATES PATENT OFFICE.

JACOB A. WEIL, OF STOCKTON-ON-TEES, ENGLAND.

GAS-PRODUCER.

1,105,474.

Specification of Letters Patent. Patented July 28, 1914.

Application filed May 16, 1914. Serial No. 839,146.

To all whom it may concern:

Be it known that I, JACOB ALBERT WEIL, a subject of the King of Great Britain, residing in Stockton-on-Tees, England, and whose post-office address is Bowesfield Lane, Stockton-on-Tees, in the county of Durham, England, have invented certain new and useful Improvements in Gas-Producers, of which the following is a specification.

10 My invention relates to gas producers of the type having a rotary grate which consists of a conical portion mounted on a cylindrical portion.

According to the invention the cylindrical part of the grate is an oblique cylinder, that is to say a cylinder having its axis inclined to its base. By this construction there is secured a crushing action on the clinker or fuel between the periphery of the cylinder and the casing of the producer, accompanied by a stirring effect on the fuel and a working of the ash down into the water trough. These actions may be enhanced by corrugating the periphery of the cylinder, whereby also the ash is prevented from being merely moved in a circle.

In the accompanying drawings Figure 1 is a vertical section, partly in elevation, through the lower part of a producer constructed according to the invention, and Fig. 2 is a plan thereof.

The grate consists of the oblique cylinder *a* having the conical grate *b* mounted on it. In this construction, which is preferred, the base of the cylinder is concentric with the casing *c* of the producer. As in the known constructions, the grate is fixed to the water trough *d* mounted to rotate on a ball bearing

and driven by a worm gear *e*. The ashes are removed from this trough by the well known method adopted for a mortar mill having a rotating pan, namely by an inclined fixed scraper *f*.

g is the usual blast pipe. The periphery of the cylindrical portion of the grate may be corrugated as at *h*.

Having thus described the nature of the said invention and the best means I know of carrying the same into practical effect, I claim:

1. In a gas producer of the type herein referred to, a grate the cylindrical portion of which is an oblique cylinder.

2. In a gas producer of the type herein referred to, a casing and a grate the cylindrical portion of which is an oblique cylinder, the base of the said grate being concentric with the said casing.

3. In a gas producer of the type herein referred to, a grate, a cylindrical portion of the said grate constructed as an oblique cylinder and a corrugated periphery to the said cylindrical portion.

4. In a gas producer of the type herein referred to, a cylindrical portion of the said grate constructed as an oblique cylinder and having its base concentric with the said casing, and a corrugated periphery to the said cylindrical portion.

In testimony whereof I have signed my name to this specification in the presence of two subscribing witnesses.

JACOB A. WEIL.
